METHOD OF AND APPARATUS FOR
WINDING ROTORS

Harry C. Stearns, Chicago, Ill., assignor to Products Development, Inc., Chicago, Ill., a corporation of Illinois

Application May 7, 1942, Serial No. 442,133

9 Claims. (Cl. 242—13)

This invention relates to armature winding and to a method of and apparatus for the mechanical winding of the same.

The primary object of the invention is to provide novel apparatus for winding armatures.

A further object of the invention is to provide a novel method of winding armatures.

Still a further object of the invention is to provide a novel method of and apparatus for winding simultaneously a plurality of armatures.

Another object of the invention is to provide a novel method of and apparatus for winding armatures in which the wire is laid into the slots of the armature evenly and without in any way stressing the wire.

A further object of the invention is to provide a novel method of and apparatus for the winding of armatures wherein the danger of scraping, injuring, breaking, or in any way changing the resistance of the wire during winding is eliminated.

Another object of the invention is to provide novel and improved apparatus for carrying out the method of my invention which will be positive in action and simple and fool-proof in construction.

Certain objects of the invention lie in the provisions of specific mechanical movements whereby a plurality of armatures are caused to pass through a certain cycle of mechanical movements in order that all of said armatures may be simultaneously wound.

With the foregoing and other objects in view which will appear as the description proceeds, the invention consists of certain novel features of construction, arrangement and combination of parts, procedures, modes and steps of practice hereinafter fully described, illustrated in the accompanying drawings, and particularly pointed out in the appended claims, it being understood that various changes in form, proportion, size and minor details of structure, and in details of procedure of the method may be made without departing from the spirit or sacrificing any of the advantages of the invention.

For the purpose of facilitating an understanding of my invention, I have illustrated in the accompanying drawings a preferred embodiment of the apparatus thereof from an inspection of which, when considered in connection with the following description, my invention, its mode of construction, assembly, operation and practice, and many of its advantages should be readily understood and appreciated.

Referring to the drawings in which the same

characters of reference are employed to indicate the corresponding or similar parts throughout the several figures of the drawings:

Fig. 1 is a side elevational view of the apparatus of my invention with portions broken away and other portions shown in section.

Fig. 2 is an end elevational view of the apparatus with portions broken away and certain other portions being shown in section.

Fig. 3 is a top plan view on an enlarged scale showing the manner in which the wire is laid into the slots.

Many factors have prevented the use of mechanical means for the winding of armatures for small motors or dynamos, and especially for high voltage, high-frequency generators, such as used in communications. For example, the problem is illustrated by a high frequency small generator having a terminal voltage well over a thousand, and utilizing about 600 turns of #36 enamel wire in the very small slots of an armature of a few inches in diameter.

Methods heretofore employed require mounting each individual armature in a jig or fixture whereby the ends of the shafts can rotate about the central transverse axis of the armature so that each of the slots within which the wire is to be laid is substantially an arc of the cylinder of rotation defined by the ends of the slots as the armature is rotating. The surface upon which the wire is laid down is obviously substantially cubical. Flanges are used to guide the wire into the slots.

In said prior methods acceleration and deceleration of the wire is caused during the winding of the same with resultant stretching and contracting of the wire during each revolution. This stretching and contracting of the wire causes breaks in the enamel covering, cracks and frequently a complete breaking of the wire. In these prior methods it also is quite impossible to lay the wires evenly and to prevent the insulation from being weakened. Furthermore, for each skein wound, a new setting of the fixture or jig upon which the armature is mounted, including a complete removal of the armature, is usually required. Also, an attendant is required to operate and watch over each armature winding device. In order to maintain any program of economical production the speed of the winding must be high, giving rise to further and greater difficulties.

In my invention, a large number of armatures may be placed upon a suitable fixture and wires from as great a number of spools are threaded through appropriate guides and led to the arma-

tures. Each of the wires is guided through an appropriate stationary needle to the respective armature. The fixture is moved in a vertical direction, say downwardly causing a wire to be laid in a slot of each armature; then each of the armatures is rotated a certain number of degrees without movement of the fixture laying the wire across an end of each of the armatures; then the fixture moves in an upward vertical direction, laying the wire in a predetermined second slot of each of the armatures; then the armatures are each rotated simultaneously in the opposite direction from the previous rotation laying the wire across the opposite end of each of the armatures to thereby complete a single turn. The fixture is then once more moved through the same cycle until the required number of turns has been applied between the two given slots of each armature. When a skein, i. e., the given number of turns, has been applied, the lead wires are pulled from the slots and fastened temporarily, and each of the armatures is moved in its holder, relative to the socket a slight amount to permit the wire to be laid into the next given pair of slots. This is continued until the entire armature in the group of armatures being wound is completely wound. It will be clearly apparent that the time required to wind one armature or the entire group will be substantially the same. Obviously only one attendant is needed to watch the entire group and the rate of production is so great that the speed of winding need be low, permitting a higher quality product and lessening the possibility of faults occurring. Since there is no scraping or cracking of the enamel on the wire, due to the constant tension therein, the efficiency of the armatures produced by my improved method is very high in comparison with armatures made by armatures made by prior methods heretofore used.

Referring now to the specific details of my invention, the apparatus used to practice same, the reference character 10 designates generally a bench or the like with which my improved apparatus is adapted to be associated. The bench may be supported as shown by any appropriate braces 11 or the like. At one edge of the bench and on each end thereof may be provided uprights 12 having slots or V-shaped guides 13 therein for example within which the opposite ends 15 of a platform 14 are adapted to be guided as said platform is moved up and down, said up and down movement being limited by the ends of the guides 13. Journalled in said braces 11 is a cam shaft 16. Said shaft 16 is rotated by any appropriate means such as for example by a pulley 17 and belt 18 driven by any appropriate engine or motor (not shown). At each end of the platform 14 on the bottom thereof, I have provided a cam follower in the form of a roller 19 or the like journalled in appropriate brackets 20 and adapted to ride upon the arcuate edge 21 of the segment cam 22 one of which is keyed to each end of the shaft 16 opposite the rollers 19.

Obviously as the cams 22 rotate, the platform 14 will be raised each time the surface 21 engages the follower 19 and will be lowered immediately that the surface 21 has been traversed by said follower.

Spaced along the platform 14 are a plurality of bearings 23 each carrying a vertically arranged collet 24 the upper end of which is in the form of a collar 25 overlying the upper end of the

bearing 23. To the bottom end of each of the collets 24 a pinion gear 26 is keyed or in other manner fixed for rotation with the collet 24. Between each pair of collets 24 a stub shaft 28 is attached to the platform 14. A spur gear 27 is attached to the bottom of each of the shafts 28 meshing with the gears 26. Instead of an ordinary gear 25 being attached to the bottom of the end collet shown at the right in Fig. 1, a master pinion 28 is so attached. The master gear 28 is considerably longer than the gears 26 for a purpose presently to be described.

From the above description it is seen that when the master gear 28 is rotated, each gear 26 and consequently each collet 24 will also rotate an identical amount through the connection of the spur gears 27, and in the same direction. The gear 28 is adapted to cause each of the collets to alternately rotate a given number of degrees in opposite directions. The number of degrees of rotation of the collets 24 is the same as the number of degrees between the two armature slots in which the turns of wire are being laid as generally explained above.

As shown in the drawings, each of the armatures 29 consists of a laminated salient pole core 30, provided with a plurality of winding slots 31 between the poles 32 extending parallel to the axis of rotation of the armature 29. Each armature 29 includes a shaft 33 and a commutator 34 properly fixed, spaced and insulated by means of various sleeves, washers, etc., the arrangement of which is of no moment so far as this invention is concerned. Each of the armatures 29 is attached to a collet 35, having its shaft 33 disposed within the inner passage of the collet and held therein by means of a set screw 36. A flange 37 is provided on the end of the collet 35 so that when same is inserted into the upper end of the collet 24, the flange will engage and overlie the collar 25 of the collet 24. Obviously the collet 24 acts as a socket for receiving the collet 35, holding same by means of the set screws 36.

Until the armatures 29 are completely wound they are each attached to one of the above described collets or sleeves 35 which is adapted to fit into the center bore of the collet 24. As the collets 24 are rotated alternately clockwise and counter-clockwise, the armatures 29 are rotated therewith. After each skein has been wound, the screw 36 is loosened and the sleeve 35 moved an amount relative to the collet 24 equal in degrees to the number of degrees between respective poles 32. Any indicating means or measuring means 55 may be used for this purpose. For example, a notch system is an ideal arrangement.

In order to rotate the master gear 28 back and forth I have provided a simple mechanism to transmit the motion from the shaft 16. I provide a large gear 39 engaging with the master gear 28 and capable of maintaining its engagement therewith at all times. In other words, the gear 39 is rather thin in comparison with the gear 28 and is journalled upon a shaft 40 fixed relative to the bench 10. As the platform 14 is raised and lowered, the gear 39 will move relative to the gear 39 axially thereof. Because of the great thickness or length of the master gear 28 the teeth of the gear 39 slide along same while meshing therewith and consequently armatures 29 can be rotated whether the platform 14 is up or down.

Referring now to Fig. 2, I have provided a second and smaller segment cam 41 keyed or in other appropriate manner affixed to the shaft 16 and

adapted to rotate therewith. The cam 41 is engaged by a stirrup lever 42 having one end 43 rotatively mounted on a fixed shaft 44 and pivoted thereby, while having the opposite end 45 formed as a rider engaging within a notch 46 or the like provided in the face of the gear 39. As the cam 41 rotates, each time one of the straight sides 47 thereof engages the inside wall of the stirrup 42 the stirrup is pivotally moved in one direction. The stirrup 42 will remain in the position to which it has been moved during the entire time that the curved surface 48 engages the side wall of the stirrup. When the cam 41 has its other straight side brought into engagement with the opposite wall of the stirrup, the stirrup will be swung in the opposite direction, in which position it will remain during the time that the curved surface 48 is in engagement with the second inner wall of the stirrup 42. This cycle will be repeated as long as the device is in operation.

In this manner the rider 45 will describe an arc centered on the shaft 40, and since the end engages the notch or slot 46 of the gear 39 said gear will rotate alternately in opposite directions a given number of degrees. The connection between the free end 45 of the stirrup lever 42 and the gear 39 may take the form of a ball and socket rider, universal joint, or any of various slider arrangements, the exact details thereof being of no great importance. The main purpose is to translate the motion of the shaft 16 to the armatures 29 so that the movement of the armatures will be timed with respect to the raising and lowering of the platform 14 by the cams 22 which are, of course, attached to the same shaft 16. Various other mechanical connections between gear 39 and shaft 16 should suggest themselves to those skilled in the art.

The armatures are adapted to be wound with wire 49 fed thereto by an appropriate needle 50 which is mounted upon the bench 10 by means of the bracket 51. The needle is adapted to lay the wires into the slots 31 and hence extends or may be made to extend into said slots. While I have shown the needle stationary, obviously same could be made with appropriate mechanism capable of causing it to move a slight amount outwardly or the like with each turn or so of the wire in order to cause the wire to be laid evenly. However, that is a mere refinement and not shown herein. The wire 49 is guided through a hanger 52 supported on the bench 10 from the spool 53. There are as many spools 53 as there are armature units being wound. The spools may be disposed upon the bench 11 or may even be arranged on a separate support. Each spool is arranged to rotate on its shaft while at the same time being rotated on an axis perpendicular to the spool shaft. The obvious purpose of this is to prevent the wire 49 from twisting while the armatures 29 are being wound. The spool, besides unwinding, is thus arranged to turn through a complete revolution for each turn of wire 49 laid into a pair of slots 31 of the armature 29.

In order to accomplish the above explained expedient of literally untwisting the wire 49 while unwinding it from its spool 52, I prefer the following described mechanism. The spool 53 is mounted on a spindle or shaft 54 which is journaled between the arms of a U-shaped bracket 55. A manually controlled brake mechanism, generally shown at 56 is provided to maintain the tension in the wire 49. The bracket 55 has a shaft 57 which is rotatively mounted in the bearing 58 supported by the bracket 59. The free

end of the shaft 57 is provided with means for rotating same at the rate of one revolution for each revolution of the shaft 16. Any desired pulley system or gear or chain and sprocket device may be used. I have shown a V-pulley 60 attached to the shaft 57 and operated by the belt 61.

In insulating the skeins of wire which are laid in the slots from the rotor 29 usual inserts of fiber paper may be used. However, I prefer coating the entire rotor 29 with a film of a liquid insulating material such as varnish or enamel and baking the same to a tough insulating film. This method is described in my copending application. By its use the difficulties of adjusting the paper inserts are eliminated.

My improved apparatus may be readily adapted for the winding of armatures having skewed rotors. Thus by substituting an appropriately shaped cam for the cam 41, the necessary compound movement of the collets 24 may be brought about whereby the wire may be wound within the skewed slots of the rotor in the same manner and with the same apparatus hereinabove described with respect to the winding of rotors with straight slots.

It should be obvious that the apparatus described herein is more or less representative and that the mechanical expedients used are not intended to be exclusive. For example, the manner of mounting the respective armature units could be varied in many ways; the rotation of the collets 24 may be accomplished by means of belts or chains; the translation of the various motions may be accomplished by other means and different types of cams and followers; and the mounting of the spools may be different than that shown.

It is believed that my invention, its mode of construction, assembly and practice, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. The method of winding a skein of wire between a predetermined pair of slots of a rotor which comprises feeding a wire strand to a feed point adjacent the rotor and laying the wire upon the rotor, then moving the rotor in a vertical direction to lay the wire into the first slot, then turning the rotor to lay the wire strand across the end thereof, then moving the rotor in a vertical direction to lay the wire in the second slot, then turning the rotor to lay the wire across the opposite end of the rotor to carry the strand back to the starting point to complete a turn, then repeating the cycle of movements until the desired number of turns of wire have been laid in the slots, simultaneously twisting the wire a complete revolution for each turn of wire laid to cause same to lay evenly.

2. A device for winding a skein of wire between a pair of slots of a rotor comprising a wire feed guide, a supporting platform adapted to be moved in a vertical direction, means on said platform for disposing a rotor thereon with its axis perpendicular to said platform, said rotor being disposed adjacent said guide, a shaft adapted to be driven, means associated with said shaft for

periodically lifting and lowering said platform, and means coupled to said shaft for periodically turning said rotor first in one direction and then in another, said last mentioned means being timed to rotate the rotor in one direction after the platform has been lifted, and in the opposite direction after the platform has been lowered, thereby executing a cycle of motion capable of causing a wire strand laid onto said rotor by said wire feed guide to be wound in a complete turn upon said rotor.

3. A device for winding a skein of wire between a pair of slots of a rotor comprising a wire feed guide, a supporting platform adapted to be moved in a vertical direction, means on said platform for disposing a rotor thereon with its axis perpendicular to said platform, said rotor being disposed adjacent said guide, a shaft adapted to be driven, means associated with said shaft for periodically lifting and lowering said platform, and means coupled to said shaft for periodically turning said rotor first in one direction and then in another, said last mentioned means being timed to rotate the rotor in one direction after the platform has been lifted, and in the opposite direction after the platform has been lowered, thereby executing a cycle of motion capable of causing a wire strand laid onto said rotor by said wire feed guide, to be wound in a complete turn upon said rotor, the upward movement causing the wire strand to be laid in one slot, the subsequent rotary movement causing the wire strand to be laid across the end to the second slot, the subsequent downward movement causing the wire strand to be laid into the second slot, and the final reverse rotary movement causing the wire strand to be laid across the second end of the rotor completing a turn.

4. A rotor winding machine comprising a plurality of wire feed guides, a platform mounting a plurality of rotors upon their axes, said platform being movable axially of the rotors, and each rotor being rotatively mounted upon said platforms, each of said guides being adjacent a rotor and adapted to lay a wire upon said rotor, means for moving said platform in a vertical direction, and means for simultaneously turning each of said rotors a given amount, said moving and turning means being timed so that each of said rotors is translated through a cycle of movements past its respective guide whereby a turn of wire is laid upon each rotor at each cycle.

5. A rotor winding machine comprising a plurality of wire feed guides, a platform mounting a plurality of rotors upon their axes, said platform being movable axially of the rotors, and each rotor being rotatively mounted upon said platforms, each of said guides being adjacent a rotor and adapted to lay a wire upon said rotor, means for moving said platform in a vertical direction, and means for simultaneously turning each of said rotors a given amount, said moving and turning means being timed so that each of said rotors is translated through a cycle of movements past its respective guide whereby a turn of wire is laid upon each rotor at each cycle, said moving and turning means including a cam mechanism periodically lifting and lowering the platform, and a second cam mechanism driving a chain of gears, each rotor being associated with one of said gears.

6. A rotor winding machine comprising a plurality of wire feed guides, a platform mounting a plurality of rotors upon their axes, said plat-

form being movable axially of the rotors, and each rotor being rotatively mounted upon said platforms, each of said guides being adjacent a rotor and adapted to lay a wire upon said rotor, means for moving said platform in a vertical direction, and means for simultaneously turning each of said rotors a given amount, said moving and turning means being timed so that each of said rotors is translated through a cycle of movements past its respective guide whereby a turn of wire is laid upon each rotor at each cycle, said moving and turning means including a cam mechanism periodically lifting and lowering the platform, and a second cam mechanism driving a chain of gears, each rotor being associated with one of said gears, and a single driver for both of said mechanisms.

7. A machine for winding a plurality of rotors having winding slots, and placing a skein of wire upon each rotor between two predetermined slots, comprising a platform movable and adapted to be guided upwardly and downwardly, a plurality of rotatable socket devices spaced along said platform and each adapted to have a rotor removably mounted therein, a plurality of wire feed guides arranged each adjacent one of said rotors and adapted to lay a strand of wire upon said rotor, a drive shaft for operating said machine, a cam mechanism coupled with said shaft for alternately lifting and lowering said platform a given amount, and a second mechanism coupled with said shaft for rotating each of said socket devices alternately in opposite directions an amount equal to the number of degrees between the two slots within which the wire is to be laid, said mechanisms being timed to cause the rotors to be translated in a cycle of movements past the wire feed guide whereby the wire will be laid upon the rotor and wound between the two slots, each cycle serving to lay one turn of wire upon each rotor.

8. A machine for winding a plurality of rotors having winding slots, and placing a skein of wire upon each rotor between two predetermined slots, comprising a platform movable and adapted to be guided upwardly and downwardly, a plurality of rotatable socket devices spaced along said platform and each adapted to have a rotor removably mounted therein, a plurality of wire feed guides arranged each adjacent one of said rotors and adapted to lay a strand of wire upon said rotor, a drive shaft for operating said machine, a cam mechanism coupled with said shaft for alternately lifting and lowering said platform a given amount, and a second mechanism coupled with said shaft for rotating each of said socket devices alternately in opposite directions an amount equal to the number of degrees between the two slots within which the wire is to be laid, said mechanisms being timed to cause the rotors to be translated in a cycle of movements past the wire feed guide whereby the wire will be laid upon the rotor and wound between the two slots, each cycle serving to lay one turn of wire upon each rotor, and means for untwisting said wire while said wire is being laid.

9. A machine for winding a plurality of rotors having winding slots, and placing a skein of wire upon each rotor between two predetermined slots, comprising a platform movable and adapted to be guided upwardly and downwardly, a plurality of rotatable socket devices spaced along said platform and each adapted to have a rotor removably mounted therein, a plurality of

wire feed guides arranged each adjacent one of said rotors and adapted to lay a strand of wire upon said rotor, a drive shaft for operating said machine, a cam mechanism coupled with said shaft for alternately lifting and lowering said platform a given amount, and a second mechanism coupled with said shaft for rotating each of said socket devices alternately in opposite directions an amount equal to the number of degrees between the two slots within which the wire is to be laid, said mechanisms being timed to cause the rotors to be translated in a cycle

of movements past the wire feed guide whereby the wire will be laid upon the rotor and wound between the two slots, each cycle serving to lay one turn of wire upon each rotor, and a plurality of reel holding mechanisms for supporting reels of wire being led to said guides, and means operated by said shaft causing said reel holding mechanisms to rotate said reels through 360° for each turn placed upon the rotors thereby preventing the twisting of said wire while same is being wound upon said rotors.

HARRY C. STEARNS.
